JAMES WEST, OF JAMAICA PLAIN, MASSACHUSETTS.

MARKING DEVICE.

Application filed June 7, 1926. Serial No. 114,041.

This invention relates to marking devices and has for its object the production of a device of this character adapted to form fine lines upon sheets of material, said device being particularly adapted for use in connection with printer's line-up tables.

This object is attained by the mechanism illustrated in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings—

Fig. 1 represents an elevation of a marking device embodying the principles of the present invention.

Fig. 2 represents an elevation of the opposite side of said device.

Fig. 3 represents a longitudinal section of same on line 3, 3, on Fig. 6.

Fig. 4 represents a longitudinal section of same on line 4, 4, on Fig. 5.

Fig. 5 represents an end elevation of the same, and

Fig. 6 represents a transverse section of same on lines 6, 6, on Figs. 1 and 2.

Similar characters indicate like parts throughout the several figures of the drawings.

In the drawings 10 is a bed plate upon which is superimposed a sheet of material 11 on which it is desired to mark lines.

Resting upon the material 11 is a plate 12 which in the drawings is shown as having one straight edge 13, but this edge 13 may in some cases be curved if desired.

Secured to the plate 12 and extending upwardly therefrom is a guide member 14 which extends lengthwise of the plate 12 parallel to the edge 13. This guide member 14 has a groove 15 cut into one face thereof as indicated in Figs. 2, 4 and 5.

Upon and adapted to travel endwise of the guide member 14 is a framework con-

sisting in part of two parallel plates 16 and 17 which straddles the guide member 14 and contacts with the opposite faces thereof. 55

These plates 16 and 17 are joined together and spaced apart relatively to each other by means of suitable studs 18.

Secured to the outer face of the plate 16 by means of the screw 19 is a strip 20, in the opposite ends of which are secured the studs 21 and 22, these studs having flat-sided projections 23 on their inner ends extending into the groove 15, the projection on the stud 22 being of less thickness than 65 the projection on the stud 21, thereby providing slight movement up and down of said projections in the groove 15 about the axis of the stud 21.

Mounted in the plates 16 and 17 and extending across the space between said plates is a fulcrum pin 24 on which is pivotally mounted a bar 25, the movable end of which has a pin 26 extending laterally therefrom on which is mounted a roller 27, another roller 28 being revolvably mounted upon the pin 24.

These rollers 27 and 28 are adapted to travel over the upper face of the guide member 14 when the framework is moved 80 lengthwise of said guide member.

The pin 26 extends into an opening 29 in the plate 16 as indicated in Fig. 2 of the drawings, this opening 29 being of greater diameter than that of the pin 26, thereby 85 permitting said bar 25 to move about the axis of the pin 24 until the periphery of the pin 26 contacts with the opposite wall of the opening 29.

The bar 25 is provided with an upwardly 90 extending ear 30 between which and one of the studs 18 are two helical springs 31 which tend under normal conditions to retain the pin 26 in contact with the lower wall of the opening 29 in its lowest position, 95 as shown in Fig. 2 of the drawings.

When in this position the plates 16 and 17 are tilted or inclined relatively to the upper face of the guide member 14, as indicated in Figs. 1 to 4 inclusive.

Secured by screws 32 to the upper part of the plate 16 is the U-shaped member 33 from which extends upwardly a knob 34 by which the device may be manipulated.

2

By means of screws 34 a reservoir 35 is secured to the plate 17, this reservoir being adapted to contain marking material which is adapted to be inserted into the reservoir 6 through a tube 36 extending across the upper end of the reservoir and having a slot 37 therein.

The outer end of the tube 36 is provided with a closing plug 38 threaded thereto. 10 By removing this plug 38, an additional supply of marking material may be admitted to the reservoir 35.

Within the opposite end of the tube 36 is the tubular shank 39 of a head 40 having 15 a wick 41 secured therein, one end of said wick projecting slightly beyond said head and the opposite end projecting through the slot 37 in the tube 36 downwardly into the marking material in the reservoir 35.

20 The outer end of the wick 41 contacts with the periphery of an inking roller 42 revolvably mounted on a stud 43 carried by a bell crank lever 44, the upper end of which is connected by means of a helical spring 45 25 with one of the studs 18, as shown in Fig. 3 of the drawings.

Between the head 40 and the reservoir 35 and surrounding the tube 36 is a helical spring 46 which forces the projecting end 30 of the wick 41 in contact with the periphery of the inking roller 42.

Below this inking roller 42 is a rotatable marker 47 revolvably mounted upon a pin 48 extending from a member 49, connected 35 by a hinge pin 50 to a plate 51 secured to the face of the plate 17.

Surrounding this hinged pin 50 is a helical spring 52 which tends to force the marking disk 47 into contact with the edge 13 40 of the plate 12.

The outer end of the pin 48 has secured thereto a finger 53 by which the marking disk 47 may be moved outwardly about the axis of the hinged pin 50 against the tension of the spring 52. As soon as released, 45 the spring 52 will again move the marking disk 47 into contact with the edge 13.

Under normal conditions with the framework tilted in the position shown in Figs. 50 1 to 4 inclusive, the marking disk 47 will be free from contact with the work.

As soon as the operator desires to draw a line upon the material 11, he seizes the knob 34 and presses the framework downwardly until the marking disk 47 contacts 55 with the material and then moves the framework lengthwise of the guide member 14, causing a line to be marked upon the material conforming to the outline of the edge 60 13 with which the marking disk is in contact.

If in any case it is desired at any time to remove the disk from contact with the edge 13, this can be accomplished by slight pressure upon the finger 53.

Owing to the inclination of the disk 47 as shown in Fig. 5, only the extreme edge of the disk 47 is in contact with the edge 13, and consequently any ink upon the periphery of the disk will not contact with said edge 13 and cause a blot or uneven line to be made upon the material.

The tension of the spring 52 will serve to maintain the marker in contact with the edge 13 while the spring 45 acting upon the lever 44 will force the ink roller 42 downwardly against the marker 47, thereby causing the edge of the marker 47 to be held in yielding contact with the material being lined, and at the same time insuring the transfer of the ink or other marking material upon the roller 42 to the edge of the marker.

The lever 44 is mounted upon a fulcrum pin 54 which rocks in the blades 16 and 17 and extends through an opening 55 in the bar 27, this opening 55 being of larger diameter than that of the pin 54, thereby permitting free movement of the bar about the axis of the pin 24. Upon the pin 54 is disposed a collar 54^a which is secured thereto by a set screw 54^b, one end of said collar bearing against the bar 25 and the opposite end thereof bearing against the plate 17. This collar 54^a thus secured to the pin 54 and so positioned between the plate 17 and bar 25 prevents any end movement or displacement of the pin 54.

This makes a very efficient device for marking lines upon paper or other material which is especially adapted for use in connection with printer's line-up tables.

It is believed that the operation and many advantages of the invention will be understood without further description.

Having thus described my invention, I claim:

1. In a device of the class described, a guide member; a plate beneath said guide member having a straight edge parallel to and at one side of said guide member; a framework adapted to travel along said guide member; a marker carried by said framework; and yielding means for retaining said marker in contact with said straight edge.

2. In a device of the class described, a guide member; a plate beneath said guide member having a straight edge parallel to and at one side of said guide member; a framework adapted to travel along said guide member; a rotatable marker carried by said framework; and yielding means for retaining said marker in contact with said straight edge.

3. In a device of the class described, a guide member; a straight edge; a framework adapted to travel along said guide member; a marker carried by said framework; means for supplying marking material to said marker; and yielding means

for retaining said marker in contact with said straight edge.

4. In a device of the class described, a guide member; a straight edge; a framework adapted to travel along said guide member; a rotatable marker carried by said framework; means for supplying marking material to the edge of said marker; and yielding means for retaining said marker in contact with said straight edge.

5. In a device of the class described, a guide member; a straight edge; a framework adapted to travel along said guide member; a rotatable marker carried by said framework; an inking roller contacting with said straight edge; a reservoir for marking material; and means for supplying marking material to said roller from said reservoir.

6. In a device of the class described, a guide member; a straight edge; a framework adapted to travel along said guide member; a rotatable marker carried by said framework; an inking roller contacting with the edge of said marker; a reservoir for marking material; and a wick extending from said reservoir with its outer end in contact with the periphery of said roller.

7. In a device of the class described, a guide member; a straight edge; a framework adapted to travel along said guide member; a rotatable marker carried by said framework and adapted to travel along said straight edge; an inking roller contacting with the edge of said marker; a reservoir for marking material; a wick extending from said reservoir; and yielding means for retaining the outer end of said wick in contact with said roller.

8. In a device of the class described, a guide member; a straight edge; a framework adapted to travel along said guide member; a rotatable marker carried by said framework; a support on said framework adapted to tilt relatively thereto; a pin on said support about the axis of which said marker is adapted to rotate; a spring for tilting said support and retaining the marker in contact with said straight edge; and means for supplying marking material to said marker.

9. In a device of the class described, a guide member; a straight edge; a framework adapted to travel along said guide member; a supporting roller; a fixed pin therefor; a bar pivotally mounted on said pin; another supporting roller on the free end of said bar; means for limiting the movement of said bar about the axis of said pin; a marker carried by said framework adjacent the free end of said bar and adapted to travel along said straight edge; and a spring coacting with said bar and forcing the free end of said bar downwardly.

10. In a device of the class described, a guide member; a straight edge; a framework consisting in part of two parallel plates adapted to straddle and travel along said guide member; a marker carried by said framework; and yielding means for retaining said marker in contact with said straight edge.

11. In a device of the class described, a guide member; a straight edge adapted to rest on the work; a framework adapted to travel along said guide member; a rotatable marker carried by said framework; yielding means for retaining said marker in contact with said straight edge; and yielding means for normally retaining said marker free from contact with the work.

12. In a device of the class described, a guide member; a straight edge adapted to rest on the work; a framework consisting in part of two parallel plates adapted to straddle and travel along said guide member having a groove extending lengthwise of one face thereof; a marker carried by said framework and adapted to travel along said straight edge; means for supplying marking material to said marker; yielding means for retaining said marker free from contact with the work under normal conditions; and projections on one of said plates disposed in said groove one of which is movable transversely of said groove and permits the movement of said marker toward the work.

13. In a device of the class described, a guide member; a straight edge; a framework adapted to travel along said guide member; a rotatable marker carried by said framework; an inking roller; yielding means for retaining said roller continuously in contact with said straight edge; a reservoir for marking material; and means for supplying marking material to said roller from said reservoir.

14. In a device of the class described, a guide member; a straight edge; a framework adapted to travel along said guide member; a rotatable marker carried by said framework and adapted to travel along said straight edge; an inking roller contacting with the edge of said marker; a reservoir for marking material; a tube extending through said reservoir and provided with a slot in the inner end thereof; and a wick extending from said reservoir through said tube with its outer end in contact with the periphery of said roller.

15. In a device of the class described, a guide member; a straight edge; a framework adapted to travel along said guide member; a rotatable marker carried by said framework and adapted to travel along said straight edge; an inking roller contacting with the edge of said marker; a reservoir for marking material; a tube extending from

said reservoir; a wick extending from said reservoir through said tube; a head on the outer end of said wick provided with a tubular shank slidable in said tube; and a spring for forcing said head toward the inking roller and causing the outer end of said wick to contact with said roller.

16. In a device of the class described, a guide member; a straight edge; a framework adapted to travel along said guide member; a rotatable marker carried by said framework; a support on said framework adapted to tilt relatively to said marker; a pin on said support about the axis of which said marker is adapted to rotate; a spring for tilting said support and retaining the marker in contact with said straight edge; a roller for supplying marking material to said marker; and yielding means for

retaining the peripheries of said roller and 20 marker in contact under all conditions.

17. In a device of the class described, a guide member; a straight edge; a framework consisting in part of two parallel plates adapted to straddle and travel along 25 said guide member; a bar pivoted at one end between said plates; a roller supported on the opposite end of said bar and adapted to travel on said guide member; yielding means for normally tilting said framework relatively to said roller bar; and a marker carried by said framework adjacent the roller supported on said bar and adapted to travel along said straight edge.

Signed by me at 746 Old South Bldg., 35 Boston, Mass., this 4th day of June, 1926.

JAMES WEST.
